UNITED STATES PATENT OFFICE.

WILLIAM L. BUEDINGEN, OF MILWAUKEE, WISCONSIN.

MUSIC-ROLL CONTAINER.

1,385,199.

Specification of Letters Patent.

Patented July 19, 1921.

Application filed March 26, 1920. Serial No. 369,128.

To all whom it may concern:

Be it known that I, WILLIAM L. BUEDINGEN, a citizen of the United States, and resident of Milwaukee, in the county of Milwaukee and State of Wisconsin, have invented new and useful Improvements in Music-Roll Containers, of which the following is a description, reference being had to the accompanying drawings, which are a part of this specification.

The present invention relates to certain new and useful improvements in containers or receptacles, and refers more particularly to a container for music rolls.

15 Numerous devices have been devised for containing a music roll therein all of which have either been considerably expensive to produce or else if produced at a comparatively low cost have been of a flimsy construction.

Hence with the above and other inherent objections to the existing devices of this character in mind, my invention has for its primary object to provide a music roll carton and method of producing the same which will be of substantial construction and at the same time comparatively cheap of manufacture.

Another object of the present invention is 30 to provide a music roll carton of the class described having a removable closure for one end thereof, having means for engaging the adjacent spool head of the music roll when the closure is being opened to project 35 the adjacent end of the music roll slightly outwardly of the carton for convenience in removing the roll therefrom, the closure and parts carried thereby being movable to a position entirely below the adjacent open 40 end of the carton to provide an unrestricted opening.

A further object of the present invention is to provide an improved method of producing a music roll receiving carton of the class described by spirally winding material to form a cylindrical tube which is then placed upon a heated mandrel and shaped to substantially rectangular form, whereby 45 a stronger and cheaper construction is provided.

A still further object of the present invention is to provide a music roll receiving carton of the class described which will present a neat appearance which will have the 50 full strength of the material used in form-

ing the same at the corners as well as in other places, and which will be capable of production at a comparatively small cost, all things considered.

With the above and other objects in view which will appear as the description proceeds my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing I have illustrated two complete examples of the physical embodiment of my invention constructed according to the best mode I have so far devised for the practical application of the principles thereof, and in which:

Figure 1 is a perspective view of one end of a music roll container embodying the features of my invention, the parts being shown as in open position with a roll about to be removed therefrom and a portion of the wrapper or cover on the container being removed to illustrate the manner of forming the container.

Fig. 2 is a view of one end of my improved carton with parts broken away and illustrating the hinge cover as in closed position, and

Fig. 3 is a fragmentary perspective view similar to Fig. 1, with the music roll removed, and of a slightly modified form of construction.

The cartons for receiving music rolls or the like now in every day use are formed from a rectangular blank of material folded and secured in assembled position, which construction is faulty in that the material is partly cut or broken at each corner, and besides being a weak and faulty construction is expensive to produce. I overcome this difficulty by first spirally winding suitable material, as at 5, to form a cylindrical tube 100 which is then placed upon a heated mandrel and shaped to substantially rectangular form and then pressed or ironed so that the same will retain its proper form.

In shaping the cylindrical tube, corners 105 6 are left slightly rounded and thus full strength of the material is obtained as will be obvious. The tubular rectangular member thus formed is then wrapped with suitable covering 7 and then one end closed in 110

any desired manner. The particular manner in which the end of the carton thus formed is closed, forms no part of the present invention, and therefore the same has not 5 been shown in the accompanying drawing. The open end of the carton is provided with a removable closure now about to be described.

The hinge cover 8 is provided with side 10 portions 9 for engagement with the inner peripheral wall of the carton adjacent the opening when the same is closed to retain the cover in position, and the lower end of the hinge cover is provided with a bottom 15 projection 10 which is hingedly connected, as at 11, with a tab portion 12. The tab portion is slideable within the carton and has secured thereto one end of a flexible securing strip 13 having its other end secured to 20 the carton, the strip 13 being sufficiently long to permit the movement of tab 12 toward the open end of the carton a sufficient distance to allow hinge 11 to project slightly beyond the carton end, and permit cover 8 to 25 drop as depicted in Fig. 1.

The cover 8 is provided with a finger engaging portion 14 for convenience in removing the same from the end of the carton, as will be obvious when the same is removed 30. The bottom projection 10 will be inclined slightly and by reason of such inclination will engage the spool head 15 of a music roll 16, disposed within the carton, and thus by reason of the friction therebetween move 35 or draw the music roll outwardly therewith to the position depicted in Fig. 1, when the same may be readily withdrawn from the carton. If desired, the projection 10 may be provided with a recess 17 to insure the 40 positive movement of the roll outwardly with the hinge cover as the spool head 15

will engage within the aperture as depicted in Fig. 2.

As depicted in Fig. 3, the projection 10 may either be rigid with the cover 8 or else 45 be hingedly connected thereto, as at 18, if desired, however, in either form the operation is the same. By my improved construction, the cover when in open position provides an unrestricted opening from the carton to permit the ready removal from the carton of the roll contained therein, which besides the production of a cheaper, but stronger carton has a decided advantage over existing devices of this character. 55

What I claim as my invention is:

1. A roll receiving carton having an open end, a cover normally closing said end, and a portion carried by the cover and slideable within the carton, said portion having a recess therein in which the adjacent end head of a roll within the carton is engageable when the cover is in closed position to insure the positive partial withdrawal of the roll from the carton when the cover is moved to open 65 position. 60

2. A device of the class described comprising a roll receiving carton having one end closed and its other end open, a cover for removably closing the open end of the carton, a bottom projection carried by the cover and engageable with the adjacent spool head of a music roll disposed within the carton, a tab portion slidably secured within the carton and hingedly connected with the bottom projection, said bottom projection having an aperture therein in which the adjacent music roll spool head is engageable whereby the same is moved outwardly of the carton upon the opening of the cover. 75 70

In testimony whereof, I affix my signature. 80
WILLIAM L. BUEDINGEN.
